UNITED STATES PATENT OFFICE.

WILLIAM THORNBURGH, OF DETROIT, MICHIGAN, ASSIGNOR, BY MESNE ASSIGNMENTS, TO T. H. SIMPSON, OF DETROIT, MICHIGAN.

DRAFT-RIGGING.

SPECIFICATION forming part of Letters Patent No. 754,958, dated March 15, 1904.

Application filed February 18, 1903. Serial No. 143,991. (No model.)

To all whom it may concern:

Be it known that I, WILLIAM THORNBURGH, a citizen of the United States, residing at Detroit, in the county of Wayne and State of Michigan, have invented certain new and useful Improvements in Draft-Rigging, of which the following is a specification, reference being had therein to the accompanying drawings.

10 The invention relates to new and useful improvements in draft-rigging; and it consists in the construction of the side plates having a tie intermediate the ends thereof, together with the particular construction of this tie and 15 its coöperation with the springs, followers, and yoke.

The invention further consists in the construction of a cross-block or abutment shouldered against the sides in a tandem draft-rigging, the springs acting against the opposite ends thereof, and, further, in the construction, arrangement, and combination of its various parts, as more fully described, and particularly pointed out in the claims.

25 In the drawings, Figure 1 is a vertical central section of my improved draft-rigging. Fig. 2 is a horizontal section therethrough. Fig. 3 is a cross-section on line $\alpha\alpha$, Fig. 2; and Fig. 4 is a sectional perspective illustrating the central abutment or cross-block, the tie, and its coöperation with the yoke, side plates, and followers.

30 A represents the usual draft-timbers in a railway-car, to which the side plates B are secured—as, for instance, by means of the bolts C.

At substantially the middle of the side plates are the vertical flanges D, separated from each other, and preferably having overhanging 40 edges—in other words, being hook shaped—to form ways for the flanges E on the central block F. This block F performs several functions, first being that of an abutment against which the inner ends of the springs G G' bear 45 to take up the end thrust thereof when these springs are compressed by the movement of the yoke H in either direction, this yoke being of the usual construction, and I there-

fore do not deem it necessary to further describe it.

The block F when it is provided with the flanges E also acts as a central tie between the two side members, and with the construction to be hereinafter described it will be obvious that it also forms a tie between the two parts 55 of the yoke; but for convenience of description I will refer to this block as a "tie-block" or a "cross-block."

I is a bottom plate fitting between the two side plates and secured in position by means 60 of cross-bolts J, this bottom plate lying in the operating parts including the cross-block.

K represents the outer followers at opposite ends, sliding between the two side plates and against which one end of the springs directly 65 abuts, and L represents the two inner followers, bearing against the cross-block and against which the two opposite ends of the springs abut.

The followers K are limited in their end- 70 wise movement by the lugs a and b, and these followers therefore necessarily project into the recesses formed by the flanges or lugs upon its side plates, while the followers L, abutting against the cross-block, may be of much smaller 75 size than usual and may be of a size to fit within the space within the flanged side walls of the side plates.

Secured to the top and bottom members of the yoke are the lugs M and N, these lugs 80 preferably being of a width corresponding to the width of the cross-block and being secured to the yoke in any suitable manner—as, for instance, by means of rivets c. These lugs M and N preferably have the ends inturned, 85 which inturned ends are provided with the flanges d, which engage in complementary guides e in the sides of the cross-block. I show in these drawings in addition to the springs G G' the auxiliary springs O to get 90 greater spring resistance. These may be used or not, according as greater or less spring resistance is required.

The parts being thus arranged and constructed, their operation is as follows: Assuming 95 that the draft-bar is moved to the left, the

right-hand follower K will compress the spring G' against the cross-block, while the lugs on the yoke will move the left-hand follower L endwise and compress the spring G 5 against the left-hand follower K. On movement of the yoke to the right or reverse of this movement the left-hand spring will be compressed against the cross-block, while the right-hand spring will be compressed against 10 the right-hand follower K.

It will be obvious from the construction shown that I get a solid abutment in the middle of the sides against which the compression of the springs may be exerted and that 15 if this abutment is provided with flanges, such as E, it will act as a tie member between the two side pieces and prevent the possibility of lateral strain being applied to said side plates even if the draft-timbers should 20 tend to warp or bend. It is also evident that the two members of the yoke are tied together by means of the interlocking lugs thereon engaging in the guide-grooves in the cross or tie-blocks.

25 The entire spring-rigging, including the cross-block, may be removed by taking out the bolts J on the bottom plate I.

What I claim as my invention is—

1. In a draft-rigging, the combination of the 30 side plates, of a tie between these plates intermediate the ends thereof, resilient means upon opposite sides of the tie, and a draft attachment adapted to operate the resilient means simultaneously, said draft attachment having 35 an interlocking engagement with the tie.

2. In a draft-rigging, the combination of the side plates, of a tie connecting the plates intermediate the ends thereof, springs on opposite sides of said tie, and the draft attachment 40 connected to act upon, and simultaneously move the springs, said draft attachment having an interlocking engagement with the tie.

3. In a draft-rigging, the combination of the side plates, of a detachable tie connecting the 45 plates at or near the middle thereof, resilient means upon opposite sides of the tie, and a draft attachment adapted to operate the resilient means simultaneously, said draft attachment having an interlocking engagement with 50 the tie.

4. In a draft-rigging, the combination of the side plates, of guides in said plates at or near the middle, and a tie-block detachably engaged in said guides, resilient means upon opposite 55 sides of the tie, and a draft attachment adapted to operate the resilient means simultaneously, said draft attachment having an interlocking engagement with the tie.

5. In a draft-rigging, the combination of the side plates, of vertical guides in said plates intermediate the ends, a tie-block detachably engaged in said guides, and a removable bottom plate for normally holding said block in position, and permitting its withdrawal when said 65 bottom plate is removed, resilient means upon

opposite sides of the tie, and a draft attachment adapted to operate the resilient means simultaneously, said draft attachment having an interlocking engagement with the tie-block.

6. In a draft-rigging, the combination of the 70 side plates, an intermediate tie-block connecting the same, the draft-yoke, and lugs on said yoke having an interlocking sliding engagement with said tie-block.

7. In a draft-rigging, the combination of the 75 side plates, a middle tie-block, followers on opposite sides of the block, the yoke, having central lugs engaging said followers, springs on opposite sides of the block within the yoke, and lugs centrally on the yoke, engaging the 80 said followers and interlocking with the tie-block.

8. In a tandem draft-rigging, the combination of the side plates, and springs, of a draw-bar adapted to operate upon the springs simultaneously, a middle cross-block shouldered against the side plates, against which the springs upon the opposite sides thereof are compressed by the movement of the draw-bar, and means for slidably interlocking the draw- 90 bar with the cross-block.

9. In a tandem draft-rigging, the combination of the side plates, middle, vertical guides, a cross or tie block engaging said guides, a removable bottom plate holding said cross or tie block in position, the yoke, hooked lugs on the yoke engaging guideways in the cross or tie block, followers on opposite sides of said block actuated by the engagement therewith of the lugs in movement of the yoke, and springs abutting against the followers between the side plates. 95

10. In a tandem draft-rigging, the combination of the side plates, of a middle cross-block, the yoke, having members on opposite sides 105 of said block, and an interlocking sliding engagement between the two members of the yoke and said block.

11. In a draft-rigging, the combination of side plates, a tie between the plates intermediate the ends thereof, resilient means upon the opposite sides of the tie, and a draft attachment adapted to simultaneously compress the resilient means, said draft attachment having a sliding interlocking engagement with 115 the tie.

12. In a draft-rigging, the combination of side plates, a detachable tie-block between the plates intermediate the ends thereof, resilient means upon the opposite sides of the tie, and a draft attachment adapted to simultaneously compress the resilient means, said draft attachment having a sliding interlocking engagement with the tie-block. 120

13. In a draft-rigging, the combination of side plates, an intermediate block between the same, a draft-yoke, and means on the yoke for slidably interlocking the same with the block.

14. In a draft-rigging, the combination of side plates, an intermediate block between the 130

same, resilient means at the opposite sides of the block, a draft-yoke, and means for loosely interlocking the yoke with the block, said block constituting an abutment for the resilient means.

15. In a draft-rigging, the combination of side plates, a detachable intermediate block between the same, a draft-yoke, and means for loosely interlocking the yoke with the block.

16. In a draft-rigging, the combination of side plates, a detachable intermediate block between the same, resilient means at the opposite sides of the block, a draft-yoke, and means for loosely interlocking the yoke with the block, said block constituting an abutment for the resilient means.

17. In a draft-rigging, the combination of side plates, a detachable intermediate block between the same, spring members at the opposite sides of the block, a draft-yoke, and means for loosely interlocking the yoke with the block, said block constituting a stationary abutment for the spring members.

18. In a draft-rigging, the combination of side plates, an intermediate block between the same, resilient means at the opposite sides of the block, a draft-yoke operatively associated with the resilient means, and means for loosely interlocking the yoke with the block, said block constituting an abutment for the resilient means.

19. In a draft-rigging, the combination of side plates, an intermediate tie-block connecting the same, resilient means at the opposite sides of the block, a draft-yoke operatively associated with the resilient means, and means for loosely interlocking the yoke with the block, said block constituting an abutment for the resilient means.

20. In a draft-rigging, the combination of side plates, an intermediate block between the same, spring members at the opposite sides of the block, a draft-yoke operatively associated with the spring members and imparting simultaneous movement thereto, and means for loosely interlocking the yoke with the block.

21. In a draft-rigging, the combination of side plates, an intermediate block between the same, spring members at the opposite sides of the block, a draft-yoke operatively associated with the spring members, and imparting a simultaneous movement thereto, and means for loosely interlocking the yoke with the block, said block constituting an abutment for the resilient means.

22. In a draft-rigging, the combination of

side plates, a detachable intermediate tie-block connecting the same, spring members at the opposite sides of the block, a draft-yoke operatively associated with the spring members, and imparting a simultaneous movement thereto, and means for loosely interlocking the yoke with the block, said block constituting a stationary abutment for the spring members.

23. In a draft-rigging, the combination of side plates, a block between the same, and a draft-yoke having an interlocking connection with the block.

24. In a draft-rigging, the combination of side plates, an intermediate block between the same, and a draft-yoke having an interlocking connection with the block.

25. In a draft-rigging, the combination of side plates, an intermediate detachable block between the same, and a draft-yoke having a sliding interlocking connection with the block.

26. In a draft-rigging, the combination of side plates, an intermediate block between the same, resilient means upon one side of the block, a draft-yoke operatively associated with the resilient means, and means on the yoke for slidably interlocking the same with the block.

27. In a draft-rigging, the combination of side plates, an intermediate detachable block between the plates, a spring member upon one side of the block, and a draft-yoke operatively associated with the resilient means, said draft-yoke having an interlocking connection with the block.

28. In a draft-rigging, the combination of side plates, a detachable intermediate block between the same, a spring member upon one side of the block, a draft-yoke operatively associated with the spring member, and means for slidably interlocking the yoke with the block.

29. In a draft-rigging, the combination of side plates, an intermediate block between the same, resilient means upon one side of the block, a draft-yoke operatively associated with the resilient means, and means for loosely interlocking the yoke with the block, said block constituting an abutment for the resilient means.

In testimony whereof I affix my signature in presence of two witnesses.

WILLIAM THORNBURGH.
